COLLAPSIBLE SIDEWALK SIGN SUPPORT

Rudolph W. Lotz, Chicago, Ill., assignor to
 Schneider Iron Works, Chicago, Ill., a corpora-
 tion of Illinois

Application August 16, 1937, Serial No. 159,260

6 Claims. (Cl. 40—125)

This invention relates to improvements in collapsible sidewalk sign supports which are cheap, durable and efficient and which may be folded to occupy a very small space so as to enable them 5 to be packed and shipped in very flat cartons.

A further object of the invention is to provide a device of this character which can be very easily set up and collapsed, respectively, by unskilled persons.

10 The invention is capable of being variously embodied and in the accompanying drawings there are illustrated two suitable embodiments thereof.

In said drawings:

Fig. 1 is a perspective view of the preferred 15 form of embodiment of the invention.

Fig. 2 is a fragmentary front elevation of the same when collapsed or folded up ready to be inserted into a flat carton of a depth substantially equal to the width of the metallic elements, mainly channel bars, of which the structure 20 is composed.

Figs. 3 and 4 are fragmentary detail sectional views on an enlarged scale taken respectively on the lines 3—3 and 4—4 of Fig. 1.

25 Fig. 5 is a fragmentary side elevation illustrating another embodiment of the invention.

Fig. 6 is a side elevation of the same showing the parts in position in full lines preparatory to disposing them in the position of Fig. 5 and in 30 the dotted line position of Fig. 6.

Figs. 7 and 8 are fragmentary detail sectional views on an enlarged scale taken, respectively, on the lines 7—7 and 8—8 of Fig. 5.

Fig. 9 is a fragmentary detail perspective view 35 of the upper end of one of the supporting legs of the structure.

Referring first to Fig. 1, it will be noted that the sign support comprises the U-shaped member 1 composed of a strip of channel bar, preferably. 40 The terminal portions of the arms of said member 1 are offset inwardly from the main portions of said arms as at 2, and to said offset portions 2 there is pivoted a swinging frame 3 of a suitable type and shape. Said frame 3 is adapted 45 to carry the sign to be displayed or may constitute a permanent portion of such sign.

Pivottally secured to the arms of said U-shaped frame 1 between the ends of the latter, are the arms 4 of a U-shaped support 5, also composed of 50 channel bar, having outwardly projecting flanges, as shown in Fig. 4. The pivoted connections between the arms 4 (which are the equivalent of legs) and the U-shaped member 1 are effected by means of rivets 6. Spaced from each of said 55 rivets 6 is an opening in each of said arms 4

which is adapted to receive a pivot member 7 extending through the same and through a spacing sleeve 1a and the terminal end portion 8 of an arm 9 of the U-shaped support 10. The said terminal end portion 8 of each of the arms 9 is offset slightly inwardly from the body portions thereof and the arms 9 of the member 10 are thus pivotally secured to the arms 4 of the member 5. Each of the arms 9 is pivotally secured between its ends to the U-shaped member 1 by means of 10 a suitable bolt 11 which extends through a spacing sleeve 12 disposed between the arm 9 and an arm of said U-shaped member 1 through which the bolt 11 projects.

The bolt 11 is removable digitally to effect collapsing of the structure shown in Figs. 1—4 inclusive when the several component parts of the structure are disposed as shown in Fig. 1. The several connections of the supports 5 and 10 with the member 1 are vertically aligned with each other and are so held by the bolt 11 when the middle portions of said supports 5 and 10 rest upon the side-walk.

When the member 1 is vertically disposed, the 25 view of the sign carried by the member 3 is unobstructed by any portion of the respective supporting members 4 and 10 and is only slightly obstructed, when viewed from an angle, by the arms of the supporting members 5 and 10.

By removing the bolt 11, the supports 5 and 10 are folded so that their side edges are aligned with each other and with the side edges of the arms of the member 1 and the side edges of the member 3, thus enabling the device to be disposed in a carton of a width substantially equal to the width of said arms and middle portion of the member 1 and of the members 5 and 10, as 30 shown in Fig. 2.

Obviously, the middle or crossbar portions of the arms or legs 4 and 9 may be omitted if desired, said arms constituting supporting legs whether connected, as shown, or not.

In the structure of Figs. 5—9 inclusive, the legs 13 are pivotally secured at their upper ends to points between the ends of the arms of the member 14, which corresponds with the member 1 and which carries a member 15 corresponding with the member 3. Said legs 13 are composed of channel bars disposed with their flanges extending outwardly and each thereof is equipped between its ends with a stud 16 shown in detail in Fig. 7 which is equipped with an enlarged head.

The legs 17, also composed of channel bars having their flanges disposed outwardly, are secured between their ends to the lower end por-

tion of the member 14 by means of suitable pivot members 18. Each of the legs 17 is provided at its upper end with a stud 19 mounted upon the rear face of the said leg and which is spaced from the pivot 18 the same distance as the pivotal connection 20 between each leg 13 and said member 14 is spaced from said pivot 18.

When the parts, 13, 14 and 17 above described are disposed in the full line position of Fig. 6, the upper end portions of the legs 17 are swung clockwise to cause the studs 19 to pass into channels of the bars 13 until said studs 19 engage the studs 16, as shown in Fig. 7. The said studs 16 constitute stop formations which will prevent further relative movement of the legs 13 and 17 in the direction last indicated, so that said legs become disposed in the position shown in dotted lines in Fig. 6 and in full lines in Fig. 5. The said studs 16 and 19 become inter-engaged by means of their overlapping flanges 22 to prevent relative lateral movements of the legs 13 and 17 and thus effect a strengthening of the structure as will be obvious.

In the instance illustrated the legs 13 may be arms of a U-shaped member such as is shown in Fig. 1, whereas the legs 17 must be free of such cross-bar connection to render them capable of being folded upwardly so that their longer ends are flush with the side edges of the upper portions of the arms of the member 14 after the legs 13 have been similarly swung upwardly on their pivots 20, whereupon all will be disposed flush with the members 14 and 15.

The pivot 18 necessarily includes a spacing sleeve 21 shown in Fig. 8 to enable said legs to be folded as last-above described.

An advantage of the structure of Figs. 5-9 inclusive, over the structure of Figs. 1-4, resides in the fact that the person setting up the sign is not required to insert any bolts or screws and this advantage, of course, is present also in collapsing the structure.

In the appended claims the members 1 and 14 are termed "sign-carriers" or "sign supports", it being obvious that the members 3 and 15 may be deemed to constitute parts of the signs to be displayed.

I claim as my invention:

1. A collapsible sidewalk sign support comprising a sign carrying member, a pair of supporting legs pivotally secured at their ends to the same at points between the upper and lower ends thereof, a second pair of supporting legs pivotally secured to the first-named legs between the ends of the latter and adapted to extend substantially perpendicularly thereto when said legs are disposed in supporting position relatively to said carrier and means detachably securing the second pair of legs to the lower end portion of said carrier at a point spaced from both said pivotal connections.

2. A sidewalk sign support comprising a sign carrier, two pairs of supporting legs disposed in inverted V-shaped formation, one pair of said legs pivotally secured to the sign carrier at a point spaced appreciably from the bottom thereof and the other pair of said legs secured between their ends to the lower end portion of said carrier at points spaced from the upper ends of said

legs, the upper extremities of said second pair of legs being engaged with the first-named pair of legs at points spaced from the pivotal connection of the latter with said carrier.

3. A sidewalk sign support comprising a vertically disposed sign carrier, a pair of normally angularly disposed outwardly extending legs pivotally secured at their upper ends to the sides of the carrier at points spaced appreciably above the bottom of the latter, a second pair of legs engaged at their upper extremities with the first-named pair of legs at points spaced from the upper extremities of the latter and extending at an opposite incline thereto and connection between the second pair of legs and the lower end portion of the carrier at points spaced from the upper extremities of said second pair of legs.

4. A sidewalk sign support comprising a vertically disposed sign carrier, two pairs of legs extending in inverted V-shaped formation relatively to each other with the upper extremities of one of said pairs of legs engaged with the other pair of legs at points spaced from the upper extremities of the latter, connection between the upper extremities of the last-named pair of legs and said side portions of the carrier at points spaced from the bottom of the latter, and connection between the second pair of legs at points spaced from their upper extremities with the lower end of the side portions of the carrier, said legs being offset laterally from each other and one pair thereof having a detachable connection included within the above mentioned connections for permitting collapsing of the structure.

5. A sidewalk sign support comprising a vertically disposed sign carrier, two pairs of supporting legs disposed in inverted V-shaped formation relatively to each other with the upper extremities of one pair of legs engaged with points spaced from the upper extremities of the other pair of legs whereby to cause the upper end portions of both pairs of legs to provide a V-shaped formation disposed substantially perpendicularly to the first-named V-shaped formation, and means engaging both pairs of said legs to said carrier at points in said legs disposed in the vertical plane of the carrier whereby to cause the latter to cooperate with said last-named V-shaped formation to define a triangle.

6. A sidewalk sign support comprising a vertically disposed sign carrier, two pairs of supporting legs disposed in inverted V-shaped formation relatively to each other with the upper extremities of one pair of legs engaged with points spaced from the upper extremities of the other pair of legs whereby to cause the upper end portions of both pairs of legs to provide a V-shaped formation disposed substantially perpendicularly to the first-named V-shaped formation, and means engaging both pairs of said legs to said carrier at points in said legs disposed in the vertical plane of the carrier whereby to cause the latter to cooperate with said last-named V-shaped formation to define a triangle, the engagement of one of said pairs of legs with one of the parts engaged thereby being detachable to permit collapsing of the structure.

RUDOLPH WM. LOTZ.
